(57) **CLAIM**

The ornamental design for a charging case, as shown and described.

DESCRIPTION

FIG. 1 is a front perspective view of a charging case showing my new design in a closed position;

FIG. 2 is a rear perspective view thereof;

FIG. 3 is a front elevation view thereof;

FIG. 4 is a left side elevation view thereof;

FIG. 5 is a right side elevation view thereof;

FIG. 6 is a top view thereof;

FIG. 7 is a bottom view thereof;

FIG. 8 is a rear elevation view thereof;

FIG. 9 is a front perspective view of a charging case showing my new design;

FIG. 10 is a cross-sectional view thereof, taken along line 10-10 of FIG 9;

FIG. 11 is a front elevation view thereof;

FIG. 12 is a rear elevation view thereof;

FIG. 13 is a left side elevation view thereof;

FIG. 14 is a right side elevation view thereof;

FIG. 15 is a top view thereof; and,

FIG. 16 is a bottom view thereof.
